[57] ABSTRACT

A new and distinct cultivar of Chrysanthemum plant named Orange Reagan, bearing medium sized orange blooms with a yellow-green center and a performance of 24-28 days.

2 Drawing Sheets

1

The present application is related to the following co-pending applications:

Application No.	Filing Date	Title
07/780,305	October 22, 1991	Reagan
07/780,304	October 22, 1991	Salmon Reagan
07/780,332	October 22, 1991	Dark Reagan (now abandoned and refiled on July 08, 1993, as continuing application Ser. No. 08/088104)
07/780,292	October 22, 1991	Coral Reagan
07/767,791	September 30, 1991	Sulfur Reagan (now abandoned and refiled on July 19, 1993, as continuing application Ser. No. 08/092942)
07/767,881	September 30, 1991	Yellow Reagan
07/780,238	October 22, 1991	Bronze Reagan (now abandoned and refiled on July 19, 1993, as continuing application Ser. No. 08/092941)
07/780,233	October 22, 1991	White Reagan (now abandoned and refiled on July 08, 1993, as continuing application Ser. No. 08/088107)

2

of unknown *Chrysanthemum morifolium* parents. The chrysanthemum named Reagan is described in U.S. patent application Ser. No. 07/780,305. The invention was discovered by Martinus van der Jagt, Langerhaarweg 161F, 2461 CJ Langerhaar, Holland in 1988. The invention has been asexually reproduced by cuttings in greenhouses at Ter Aar, Holland. The new cultivar has been found to retain its distinctive characteristics through successive propagations.

10

SUMMARY OF THE NEW PLANT

The present invention is a new and distinct variety of chrysanthemum of a medium sized bloom and orange color.

15

BRIEF DESCRIPTION OF THE DRAWINGS

The present new and distinct Chrysanthemum cultivar is shown in the accompanying drawings, the color being as nearly true as possible with color photographs of this type.

20

Sheet 1 shows the full bloom of the new cultivar; Sheet 2, top, shows various stages of bloom of the new cultivar; and

Sheet 2, bottom, shows the foliage and petiole of the new cultivar.

25

DESCRIPTION OF THE INVENTION

This new variety of Chrysanthemum is of the botanical classification *Chrysanthemum morifolium*, and is named Orange Reagan. When grown in the vicinity of Ter Aar, Holland, it has a response time of approxi-

ORIGIN AND HISTORY OF THE NEW PLANT

The new plant of the present invention comprises a new and distinct cultivar of Chrysanthemum plant which is an induced mutation by gamma irradiation of a chrysanthemum named Reagan, which in turn is a cross

mately 7½ weeks. This new variety produces medium sized orange blooms with a yellow green center having a 4 week performance (i.e., a Vase life of 24-28 days). This new variety of Chrysanthemum has been found to retain its distinctive characteristics throughout successive propagations and may be planted under greenhouse conditions in Holland between weeks fifty and thirty-five (i.e., between December 1 and August 30). Pest resistance, disease resistance and frost tolerance are unknown.

Three groups consisting of 300, 300 and 400 cuttings, respectively, of the parent Reagan chrysanthemum were irradiated at 1250, 1500 and 1750 RAD, respectively. The cultivar of the present application was taken from the second group.

The following is a description of the plant and characteristics (color designations are from R.H.S. Color Chart) that distinguish it over related known varieties and its antecedents:

Botanical classification: *Chrysanthemum morifolium*.

Bud:

Size.—Medium (Cross section ± 1.0 cm, Height ± 0.7 cm.

Form.—Round and flat.

Outside color.—Greyed-Red 180 A.

Bloom:

Size.—Medium

Fully expanded.—7-7½ cm.

Borne.—Upper portion, single flower per peduncle; 30 lower portion, plural flowers per peduncle.

Stems.—Strong, thick.

Forms.—Single (daisy).

Permanence.—Very good 24-28 Days (18°-20° C.).

Color:

Center of flower.—Immature: Yellow Green 151 C. Mature: Yellow Green 154 A.

Base of petals.—Between Greyed Orange 169A and B.

Inside of petals.—Between Greyed Orange 169A and B.

Reverse of petals.—Nearest to greyed-orange 163B tinged with red between the ribs.

Outer petals.—Between Greyed-Orange 169A and B.

Tonality from a distance.—An orange daisy with a fresh looking center having little or no pollen.

Discoloration.—Some to yellow orange 20 B.

Pollen.—Yellow-orange 14A.

Petals:

Texture.—Upperside smooth, underside smooth.

Number.—24-30 (Two rows).

Cross-section.—Convex.

Arrangements.—Imbricated.

Persistence.—Good. Petals keep straight or reflex somewhat at the edge at the end of blooming.

Fragrance.—Typical Chrysanthemum.

Disc diameter.—1.5 cm.

Reproductive organs:

Stamen.—Yellow, thick, 3 mm in length.

Pollen.—Appears at a late stage of blooming yellow orange in color.

Styles.—Green thick.

Length.— ± 5 mm.

Stigmas.—Yellow.

Width.— ± 1 mm.

Ovaries.—Enclosed in calyx.

Plant:

Form.—Spray mum meant for erect culture. Herbaceous.

Growth.—Strong.

Height.—100-125 cm.

Peduncle.—Near the top ± 14 cm, near the middle ± 24 cm, near the bottom ± 28 cm.

Internodes.—3 cm.

Flowering response.—7½ Weeks.

10 Foliage:

Color.—Upperside green 137 A, underside 137 C.

Size.—Length ± 12 cm, Width ± 9 cm.

Quantity.—22-28.

Shape.—Lobed, see photograph.

Texture.—Upperside rough, underside smooth slightly hirsute.

Ribs and veins.—Ribs well developed, veins not so developed.

Edge.—Crenated.

20

Distinguishing characteristics of the Chrysanthemum of the Reagan family are summarized below in Tables IA and IB. Each of the titled Reagans having a color designation is an induced mutation by irradiation of Reagan.

Color designation set forth in the following Tables are from the R.H.S. Color Chart.
